BASKETBALL

John W. Anderson, Cincinnati, Ohio, assignor to Hutch
Sporting Goods, Inc., Cincinnati, Ohio

Filed May 14, 1973, Ser. No. 359,956

Term of patent 14 years

Int. Cl. D21—01

U.S. Cl. D34—15 EE

FIG-1

FIG-5

FIG. 1 is a perspective view of a basketball showing my new design;

FIG. 2 is a left-end elevational view;

FIG. 3 is a right-end elevational view;

FIG. 4 is a side elevational view;

FIG. 5 is a top plan view.

Portions of the drawing are stippled to indicate color contrast without reference to specific colors.

I claim:

The ornamental design for a basketball, as shown.
